UNITED STATES PATENT OFFICE.

FRANK HINMAN PIERPONT, OF Salfords, Horley, England, assignor to LANSTON MONOTYPE MACHINE COMPANY, OF PHILADELPHIA, PENNSYLVANIA, A CORPORATION OF VIRGINIA.

EQUIPMENT FOR HANDLING TYPE MATRICES.

Application filed June 21, 1923. Serial No. 646,981.

To all whom it may concern:

Be it known that I, FRANK HINMAN PIERPONT, a citizen of the United States of America, residing at Salfords, Horley, in 5 the county of Surrey, England, have invented certain new and useful Improvements in Equipments for Handling Type Matrices; and I do hereby declare the following to be a full, clear, and exact description of the 10 same, reference being had to the accompanying drawings, forming part of this specification, and to the characters of reference marked thereon.

This invention relates to appliances or apparatus for facilitating the handling of type matrices and is particularly adapted for use with matrices such as are employed in type casting machines of the kind disclosed basically in Patent No. 625,998, dated May 20 30, 1899, especially those which are assembled in rows and columns in a die case and supported therein by a series of parallel bars resting in external side grooves in walls of the matrices and by parallel rods arranged 25 at right angles to the bars and passing through openings in the bars and central holes in the matrices. A matrix case equipment of the special kind referred to is disclosed in my application for Letters Patent 30 Serial No. 646,980 filed on an even date herewith.

It is frequently necessary to remove a matrix from the die case either for the purpose of replacing a new matrix for a worn 35 out or damaged one or for substituting therefor a matrix having another character or symbol; and when this is to be done, it is necessary to remove the entire series of matrices from the die case, since the rows of 40 matrices have to be separated to free the matrices of a row from the suspension devices and allow the removal of the matrix to be dealt with.

The matrices are a comparatively accurate 45 or tight fit within the die case frame and at least one entire series of suspension devices has to be withdrawn, in the case of the special equipment referred to, before the matrices as a whole can be removed from the 50 die case. In such circumstances, when the rows are separated; even on a flat surface, to enable the matrix that is to be dealt with,

to be separated from adjacent matrices and from the suspension devices, the matrices of the entire series are likely to be displaced 55 or upset, and would all have to be accurately reassembled and packed tightly together before they could be replaced in the die case, thus causing considerable trouble and a loss of time, and probably, also, damage to the 60 matrices.

It is the chief object of the present invention to obviate these drawbacks and disadvantages, and to provide an apparatus or appliances whereby the matrices can be removed as a body from the die case, the rows 65 of matrices separated and a matrix removed and changed or replaced, and the entire series of matrices thereafter returned to the die case, in an easy, speedy and efficient 70 manner without the danger of displacing or damaging any of the matrices of the series.

According to this invention, the appliances or apparatus comprises a transferring frame or carrier, which is adapted to fit 75 around the matrices while in the die case, and in which the matrices are removed from the die case; a receiving or assembling plate or tray to which the matrices are transferred by the transferring frame and whereon they can be opened up or separated, and a lifting bar or holder furnished with pins or projections adapted to enter the suspension holes in a row of matrices when one side of such row has been exposed. 80

In the die case for use with which the invention is particularly applicable, the matrices are oblong bodies rectangular or square in cross section having external lateral suspension grooves on two sides and a central suspension hole through the body at right angles to the grooves. A series of suspension bars rest in the side grooves in the matrices so that the opposite ends of the bars project from both ends of the rows of matrices and are supported by these projecting ends in slots or grooves in the sides of the matrix frame, and suspension rods pass through the central openings in the matrices and holes in the suspension bars, 90 and are supported by their opposite ends in holes in the sides of the matrix frame, being capable of being withdrawn endwise from these bearings. 95

Referring to the accompanying drawings:—

Fig. 1 is a plan view of the transferring frame or carrier.

5 Fig. 2 is a section on the line 2—2 of the frame shown in Fig. 1.

Fig. 3 is a plan of the receiving or assembling tray or plate.

10 Fig. 4 is a transverse section on the line 4—4 of Fig. 3.

Fig. 5 is a plan of the lifting bar or holder.

Fig. 6 is a front elevation of the bar shown in Fig. 5.

15 Fig. 7 is a sectional elevation of the frame, the tray and a die case in relative cooperative positions.

Fig. 8 is a sectional elevation showing the frame and plate together.

20 Fig. 9 is a plan showing the plate and lifting bar together, and

Fig. 10 is a front elevation of the lifting bar with some matrices thereon.

25 The transferring frame or carrier is represented by the character 11; the assembling or receiving plate or tray is shown at 12; the lifting bar or holder at 13; the die case at 14; and its perforated cover plate at 14' (Fig. 7); the matrices at 15; and the matrix suspension bars at 16.

30 Conveniently the transferring frame 11 (see Fig. 1) is formed of a single piece so as to be absolutely firm and rigid. The opening in the frame 11 is the same as that in the die case 14, so that the frame 11 fits over the exposed or character ends of the matrices 15 in the die case and clamps them tightly together. In the upper parts of the two end walls of the frame 11 are formed

40 open ended slots 17 adapted to receive the projecting end of the matrix suspension bars 16.

45 In order to transfer the matrices as a body to the transferring frame 11 the cylindrical matrix suspension rods (not shown) are first withdrawn from the matrices and the die case through the openings 18 in one end of the die case frame, leaving the matrices supported on the suspension bars 16.

50 The die case 14 is then turned with the character ends of the matrices upward and the frame 11 is placed over the matrices so that the character ends thereof project into the opening in the transferring frame 11.

55 The die case 14 and frame 11 are then inverted, as one, and the matrices pushed out bodily from the die case into the frame 11, so that the ends of the suspension bars 16 pass into the slots 17 (see Fig. 7).

60 As the matrices are a comparatively tight fit within the frame of the die case it is generally necessary to apply a forcing pressure to their rear ends and for convenience in doing this the receiving tray or plate 12 is furnished with a number of legs or pushers 19,

65 usually four, which are adapted to pass

through perforations in the perforated cover plate 14' of the die case and enter the cone holes or cavities 20 in the rear ends of say the four corner matrices so that by placing the plate 12 over the die case and pushing it downward, these pushers force the matrices in a body from the die case 14 into the transferring frame 11 (see Fig. 7).

The receiving or assembling tray or plate 12 is then removed and rested upon the 75 pushers 19 which now serve as legs or feet for the plate 12, and the transferring frame 11 with the matrices 15 is inverted and placed on the plate 12 so that the suspension bars 16 still between the rows of matrices 80 run across the plate 12 (see Fig. 8).

The receiving or separating plate or tray 12 is furnished with upstanding side guide walls or bars 21, and the width of the plate within these bars 21 is just equal to the length of a row of matrices, the length of the plate being longer than its width. The ends of the matrix suspension bars 16 are adapted to rest upon the upper surface of the bars 21.

90 The matrices are transferred from the transferring frame 11 by pushing them bodily from the frame 11 on to the plate 12. The height of the bars 21 is such that, while the ends of the matrix-suspension bars 16 rest on these bars, the ends of the matrices rest upon the surface of the plate and conveniently a series of parallel flat topped ribs 22 are formed on the upper surface of the plate to support the matrices (see Figs. 3 and 4).

100 The matrices now rest upon the plate 12 with their character or symbol ends upward and by gripping the ends of any of the suspension bars 16 and moving it lengthwise of the plate so as to move one or more rows of matrices away from the others, one side of any row of matrices can be exposed, such row being the one in which is situated the matrix that is to be dealt with (see Fig. 9).

110 The lifting bar 13 is now employed to lift this row of matrices clear of the others.

The bar 13 is furnished with a series of projections or pins 23 (see Figs. 5 and 6) which are of a length to penetrate through the central holes 15' of one row of matrices only and to facilitate the entry of these pins 23 into the matrices on the ends of the bar 13 are formed notches or shoulders 24 so that these, by engaging the tops and the inside of the bars 21 on the frame 12 guide the lifting bar and hold it so that the pins 23 are on a level with the holes 15' in the matrices.

115 When the pins 23 are pushed into the holes in the matrices the entire row of matrices can be lifted and the required matrix removed from its respective supporting pin and replaced (see Fig. 10).

120 When a matrix has been replaced on the pin on the bar 13, the row of matrices is 125 returned to position on the plate 12 and all

the rows brought close together again. The transferring frame is placed around the matrices and these are then retransferred to the die case and the suspension rods reinforced.

Although the apparatus has been described as employed to facilitate the changing of matrices, it can be employed equally well for loading or filling an entire die case with matrices. In this case the matrices can be assembled line by line on the lifting bar 13 together with the necessary suspension bar or bars and transferred to the receiving plate or the matrices can be assembled line by line by hand in the receiving plate and the suspension bars inserted. After the matrices have been assembled on the plate 12, they can be transferred to the frame 11 as already described and placed by the frame 11 in the die case.

I claim:

1. Apparatus for facilitating the handling of type matrices comprising a transferring frame adapted to enclose a group of matrices, a receiving or assembling tray or plate adapted to receive the matrices and retain them in position and a lifting bar or holder adapted to engage and separately support a line or series of matrices.
2. In apparatus for facilitating the handling of type matrices, the combination with a transferring frame furnished with a series of slots in two of the walls thereof, of a receiving or assembling tray or plate having side walls or bars to confine and support the matrices from or for the transferring frame.
3. In apparatus for facilitating the handling of type matrices, the combination with a tray having walls to confine and guide a series or groups of matrices, of a lifting bar furnished with projections to receive and support matrices and having guides, notches, or shoulders to engage the walls of the tray.
4. In apparatus for facilitating the handling of type matrices, a frame furnished with an opening to embrace or clamp a series of matrices and furnished in two of its opposite walls with open ended grooves or slots to receive the ends of suspension bars disposed between the rows of matrices.
5. In apparatus for facilitating the handling of type matrices, a plate or tray having upstanding walls or bars to sustain, guide or support a series or group of matrices and matrix-suspension bars.
6. In apparatus for facilitating the handling of type matrices, a lifting bar or

holder furnished with a series of pins or projections to support matrices, and with shoulders for guiding and supporting the 60 bars.

7. Apparatus for facilitating the handling of type matrices assembled and supported on bars in a matrix case, comprising a frame adapted to fit over the ends of said matrices, 65 said frame being provided with slots in opposite walls thereof to receive the said bars, and a tray provided with projecting pushers each adapted to contact with a matrix in transferring the matrices from the case to 70 the frame, said tray being also provided with a suitable surface to receive the matrices from the frame.

8. Apparatus for facilitating the handling of type matrices assembled and supported on bars in a matrix case, comprising a frame adapted to receive said matrices from the matrix case and having slotted end walls to receive said bars, a tray having a matrix receiving surface of a width equal to the 75 length of a line of matrices, said surface having a greater length than its width, and side guide walls upstanding from said surface to receive and support said bars and to support the end walls of said frame in transferring the matrices from said frame to said tray.

9. As an article of manufacture, a frame to receive matrices assembled and supported on bars in a matrix case, said frame being 90 provided with slots to receive the said bars, a tray provided with pushers for transferring the matrices from the case to the frame and provided also with a matrix receiving surface and upstanding side walls 95 to support the slotted walls of the frame during the transfer of the matrices from the frame to the tray and to receive and support the said bars, and a holder provided with projections for entering recesses in the 100 matrices and with shoulders for cooperating with the said side walls of the tray, said holder being adapted to receive a line of matrices on the tray for removal therefrom.

10. An apparatus for facilitating the handling of type matrices comprising a transferring frame or carrier, an assembling or receiving plate or tray and a lifting bar or holder arranged and combined to operate substantially as and for the purposes herein 110 described or shown in the accompanying drawings.

FRANK HINMAN PIERPONT.
